UNITED STATES PATENT OFFICE.

HERMAN E. ESCH, OF CHERRYVALE, KANSAS.

DESIGN FOR A FOUNTAIN.

Application filed September 27, 1928. Serial No. 28,290. Term of patent 14 years.

To all whom it may concern:

Be it known that I, HERMAN E. ESCH, a citizen of the United States, residing at Cherryvale, in the county of Montgomery and State of Kansas, have invented a new, original, and ornamental Design for Fountains, of which the following is a specification, reference being had to the accompanying drawing, forming part thereof.

The figure is a perspective view of a fountain showing my new design.

I claim:

The ornamental design for a fountain, as shown.

HERMAN E. ESCH.
